UNITED STATES PATENT OFFICE

160,938

OVERHEAD SPACE HEATER OR SIMILAR ARTICLE

Harry R. Greene, Pasadena, Calif., assignor to
Affiliated Gas Equipment, Inc., Cleveland, Ohio,
a corporation of Delaware

Application September 24, 1949, Serial No. 5,155

Term of patent 14 years

(Cl. D81—10)

To all whom it may concern:

Be it known that I, Harry R. Greene, a citizen of the United States, residing in Pasadena, in the county of Los Angeles, State of California, have invented a new, original, and ornamental Design for an Overhead Space Heater or Similar Article, of which the following is a specification, reference being had to the accompanying drawing, forming a part thereof.

Figure 1 is a front elevational view of the overhead space heater or similar article showing my new design.

Figure 2 is an end elevational view of the overhead space heater.

Figure 3 is a top plan view of the overhead space heater.

I claim:

The ornamental design for an overhead space heater or similar article, as shown.

HARRY R. GREENE.
